UNITED STATES PATENT OFFICE.

BRUNO LUNA, OF ROSEBUD, TEXAS.

CIGAR AND CIGARETTE HOLDER.

Application filed December 12, 1923. Serial No. 680,087.

To all whom it may concern:

Be it known that I, BRUNO LUNA, a citizen of the Republic of Mexico, residing at Rosebud, in the county of Falls and State of Texas, have invented certain new and useful Improvements in Cigar and Cigarette Holders, of which the following is a specification.

This invention relates generally to smokers' accessories, having particular reference to a holder for individual cigars or cigarettes, adapted to contain the same while being smoked, and which permits of them being safely carried in the pocket in a lighted condition.

The invention has for an object to provide a novel cigar and cigarette holder of this type, characterized by simplicity of construction and by complete removal of danger of the cigar or cigarette setting fire to the pocket if inserted in the latter in a lighted condition, while at the same time it permits of the cigar or cigarette being smoked without the need of removal from its enclosing chamber.

For further comprehension of the invention, and of the objects and advantages thereof, reference will be had to the following description and accompanying drawings, and to the appended claims in which the various novel features of the invention are more particularly set forth.

Fig. 1 of the drawings is a perspective view showing the invention as embodied in a cigarette holder.

Fig. 2 is a longitudinal sectional view thereof.

Fig. 3 is a detail perspective view of the cup in which the end of the cigarette or cigar engages.

Fig. 4 is a side elevation showing the holder as having its barrel made up of a number of sections whereby its length may be increased, the various sections being shown as separated from one another.

Fig. 5 is a fragmentary longitudinal sectional view showing a means for preventing passage of air around the cigar or cigarette in the holder.

Fig. 6 is a transverse sectional view thereof taken on the line 6—6 of Fig. 5.

Referring now to the embodiment of the invention shown in Figs. 1 to 3, my improved holder comprises a main body in the form of a tube or barrel 10 which is of suitable interior diameter to have the article to be smoked fit fairly snugly therein. This bar-

rel is circumferentially recessed at its forward end to frictionally receive a cap 11 in the end of which are holes 12. At its rear end this barrel 10 is interiorly recessed to receive frictionally the forward end of a cup 14 in which the cigarette, indicated at 15, rests. This cup has an opening 16 in the bottom thereof and is slotted from the top downward on opposite sides as at 17 to enable to better grip the wall of the barrel.

This cup 14 is formed with exterior screw threads 18 whereby it may have attached thereto a stem or mouth-piece 19 which fits over the lower end of the cup and is interiorly screw threaded at its forward end to engage the threads 18. The forward end of this mouth-piece may be exteriorly knurled as at 20 to facilitate turning. Over the rear portion of the mouth-piece a tubular casing 21 is fitted and serves to prevent the mouth-piece from contact with exterior objects, this casing fitting frictionally over the mouth-piece 19 just to the rear of the knurled member 20 thereon. The cap 11 may have a clip 23 thereon whereby the holder may be secured to the lip of the pocket in which it is being carried.

In Fig. 4 I have indicated a lengthened construction of the holder which is the same as that shown in Figs. 1, 2 and 3 except that the barrel is made up of a number of sections 10' adapted to fit one into the end of the other so that the device may be varied in length to suit requirements by varying the number of sections employed.

In Figs. 5 and 6 I have shown a further development of the invention whose purpose is to ensure of a snug fit of the cigarette in the cup 14 and thereby ensure of the air passing through the cigarette and not along the sides thereof. In this construction the cup 14 is provided with four of the slots 17 and has a frusto-conical flange element 30 on its upper end which is adapted to be engaged by a complementary ring 31 slidable in the barrel 10 so as to compress the lip of the cup against the cigarette. The ring 31 has a pair of pins 32 projecting oppositely therefrom through short longitudinal slots 33 in the barrel and adapted to be engaged to press the ring downwardly over the cup. In this construction the cup has a circumferential flange 34 formed thereon near its lower end which abuts against the end of the barrel, while the mouth-piece 19

is screwed on the said end of the barrel and clamps the cup in position.

It is believed that the manner of use of my improved device will be readily understood from the above description, the cap 11 being removed and the cigarette placed in the barrel 10 and lighted, the member 21 being first removed from the mouth-piece 19. The cap 11 is then replaced and the cigarette smoked in the usual manner, and, as will be apparent, it may be placed in the pocket in a lighted condition without any danger of setting fire to the latter.

Having thus described my invention what I claim as new and desire to protect by Letters Patent of the United States is as follows:

1. A holder of the type specified comprising a barrel, an apertured cap fitting removably thereon at one end, an apertured cup fitting removably in the other end of the barrel, and a mouth-piece fitting removably on said cup, and a guard element fitting removably on said mouth-piece.
2. A holder of the type specified comprising a barrel, an apertured cap fitting removably thereon at one end, an apertured cup fitting removably in the other end of the barrel, and a mouth-piece fitting removably on said cup, and means for contracting the mouth of said cup.
3. A holder of the type specified comprising a barrel, an apertured cap fitting removably thereon at one end, an apertured cup fitting removably in the other end of the

barrel, and a mouth-piece fitting removably on said cup, and means for contracting the mouth of said cup, said means comprising a ring slideable in the barrel and adapted to engage the rim of said cup, said cup being longitudinally slotted from said rim inward.

4. A holder of the type specified comprising a barrel, an apertured cap fitting removably thereon at one end, an apertured cup fitting removably in the other end of the barrel, and a mouth-piece fitting removably on said cup, and means for contracting the mouth of said cup, said means comprising a ring slideable in the barrel and adapted to engage the rim of said cup, said cup being longitudinally slotted from said rim inward, said ring and the cup rim having complementary engaging frusto-conical faces.

5. A holder of the type specified comprising a barrel, an apertured cap fitting removably thereon at one end, an apertured cup fitting removably in the other end of the barrel, and a mouth-piece fitting removably on said cup, and means for contracting the mouth of said cup, said means comprising a ring slideable in the barrel and adapted to engage the rim of said cup, said cup being longitudinally slotted from said rim inward, and studs on said ring projecting through longitudinal slots in the barrel for adjustment of the ring.

In testimony whereof I have affixed my signature.

BRUNO LUNA.
